UNITED STATES PATENT OFFICE.

ERNEST LODGE WILSON, OF LONDON, ENGLAND.

CURTAIN RUNNER.

Application filed March 7, 1923. Serial No. 623,504.

To all whom it may concern:

Be it known that I, ERNEST LODGE WILSON, a subject of the King of Great Britain, residing at London, England, have invented certain new and useful Improvements in and connected with Curtain Runners, of which the following is a specification.

This invention relates to curtain runners, 10 of the type described in specification No. 1,839,247 and other runners having rollers, adapted to run on a flat strip race.

When a curtain is suspended on a large 15 number of runners, although it can be drawn freely in one direction the drawing of the curtain in the opposite direction is apt to meet with a resistance due to the contact of the rollers of adjacent runners.

The object of the invention is to avoid 20 this interference between the rollers of adjacent runners and to protect the rollers from dust and damp atmosphere, with these objects in view the invention consists in the provision of guards on the runners, which, 25 when a number of runners are drawn close together will hold the rollers sufficiently apart to permit of free rotation.

In the accompanying drawings:

Figures 1 and 2 are respectively a side 30 and a front view of one form of guard applied to a wire runner.

Figures 3 and 4 are respectively a side and a front view of another form suitable for a wire runner, but detached.

Figures 5 and 6 are side views of other 35 forms of guard provided on a flat strip runner.

Figures 7 and 8 are respectively a side view and a rear view of another form of 40 flat strip runner provided with a guard.

Figure 9 is a rear view of a short piece of race with several runners in contact thereon.

In the form of invention illustrated by 45 Figures 1 and 2 a guard 1 of rectangular prismatic form is pressed up from sheet steel or other suitable material. It has triangular downward extensions 2 having indentations or pockets 3 and so curved as 50 shown in Figure 1 that when the guard is forced onto the runner it is clipped onto the wire 4 of the runner and encases the roller 5 without touching it and without interfering with it or with the pivotal action of the 55 runner. The indentations receive the adja-

cent portions of the wire and the lower parts of the extensions 2 conform to the curvature of the wire at the inturned parts 6, 6, with which the runner is provided for the purpose described in the before mentioned specification. The form of guard described is closed at the ends 7, 7, as well at the sides and top so that it forms a dust cap for the roller 5.

In the form shown in Figures 3 and 4 65 the guard is made dome shaped and pressed up from a single piece of metal.

The forms of guard above described are adapted to be removably secured to the runner, but they may be permanently secured 70 to it by soldering or otherwise.

In the form shown in Figures 5 and 6 each guard is made in one piece with the frame of a runner made of flat strip material, Figure 5 showing a rectangular prismatic guard and Figure 6 a dome shaped 75 guard.

The rollers for these forms of runner may be made without flanges but slightly broader for instance as shown in the form 80 illustrated in Figures 7 and 8.

The invention is not limited to runners having frames of the peculiar curvature illustrated as the guard may be variously formed to suit the shape of the frame. 85

I claim:

1. A guard for the roller of a curtain runner having a roller adapted to run on a flat strip race and having a frame depending from said roller, said guard having a 90 hollow body adapted to encase said roller without touching it, and having clipping members adapted to clip onto the frame of said runner to provide the sole support for the guard.

2. A guard for the roller of a curtain runner having a roller adapted to run on a flat strip race and having a wire frame depending from said roller, said guard having a hollow body adapted to encase said roller without touching it and having clipping members shaped to conform to the adjacent portions of said frame when forced onto said frame, the cooperation of the clipping members and frame serving as the sole support for the guard in its relation to the roller. 105

In testimony whereof I have signed my name to this specification.

ERNEST LODGE WILSON.
